UNITED STATES PATENT OFFICE

2,344,027

PRODUCTION OF CARBON BLACK

Leonard M. Conner, Sunray, Tex., assignor to
Continental Carbon Company, a corporation of
Delaware

Application May 5, 1941, Serial No. 392,021

4 Claims. (Cl. 23—209.8)

This invention relates to a method of producing carbon black and more particularly to a method by which the production of carbon black may be increased from a given plant while maintaining the product more uniform.

The customary method of manufacturing carbon black is to burn hydrocarbon gases under a system of steel channels upon which the carbon is deposited. In practice many thousands of lava-tipped gas flames are so placed with reference to the steel channels that the flame from each of the burners impinges directly upon a steel channel and spreads over the bottom surface thereof. The channels are moved slowly back and forth over the burners. The channels themselves are stationed in the upper portion of a burner building which normally accommodates a considerable number of parallel steel channels. For example, a typical building may be ten feet wide, one hundred eighty feet long and contain ten parallel steel channels, each approximately eight inches in cross section. The whole channel system is mounted on a track which is slowly reciprocated over the burners, the movement being approximately eight feet in fifteen minutes. The burners are located at intervals of about eight inches and are so adjusted as to produce a luminous-type flame of fish-tail shape with the flat sides of the flame at right angles to the longitudinal edges of the channel.

With so many burners in a single building the amount of air available for combustion is largely controlled by the natural draft openings in the top and bottom of the building. In general practice the amount of air available below the burners is so adjusted that the flame has the appearance of being slightly deficient in air. As a result of this method the top portion of the building above the flames contains a blanket of smoke which hangs in the upper portion of the building and generally extends down to and over the flames, partially obscuring them. If too little air is supplied the smoke blanket will drop so low that the flames are smothered. On the other hand, if there is too much air the blanket lifts above the flames and these then burn brightly without producing much carbon.

The quality of carbon black produced, as indicated by the usefulness of the product for its desired functions, primarily in mixing at other periods, is seriously affected by the combustion conditions in the system. A properly balanced, slightly smothered combustion produces not only the most carbon black but the best carbon black.

The use of the present invention has resulted

in commercial production of a greater quantity of carbon black from a given unit in a given time, and has at the same time decreased the variation in the quality of the carbon black so as to produce very much less low grade material.

The combustion operation, depending as it does upon natural drafts, is extremely susceptible to changes in the draft. These changes may be effected by a number of elements. A heavy rain has the same effect on the combustion conditions of a carbon black plant as a hard wind. In other words, the buildings cool and lighten up in a hard rain and also the same in a hard wind. 10 In both cases more gas will be put through the plant by operation of the control. Of more frequent importance are the diurnal changes in temperature, which, in many localities producing natural gas, are as much as 30°-40° F. on the average. The ordinary carbon black plant has many buildings of the type just described, and it has not proved practical to readjust the drafts with every change in weather conditions. Furthermore, it has not proved economical to provide drafts which can be easily controlled. 15 The burner structures are usually very crude affairs and draft control would have to be by very crude methods. The draft is not the only factor controlling combustion conditions, and 20 the present invention is designed to control combustion conditions irrespective of draft conditions, but also will tend to maintain a substantially uniform draft under most circumstances.

The preferred form of the invention is to provide automatic means for providing more gas whenever the temperature at a predetermined point in the burner house falls below a predetermined value and less gas whenever it rises above this value.

25 The invention is illustrated in the drawings in which Figure 1 is a vertical section taken along the line 1—1 of Figure 3 showing a typical burner house, illustrated somewhat diagrammatically; Figure 2 is a schematic view showing the operation of applicant's preferred control system; Figure 3 is a longitudinal section taken along the line 3—3 of Figure 1, looking in the direction of the arrows; and Figure 4 shows a diagrammatic plan view of one arrangement of the gas feeding system.

30 As shown in the drawings, the burner house 10 is made up of metal sheets 11, loosely assembled to provide air. At an upper portion of the building is a series of 8" channel members 12 beneath each of which is provided a row of lava-

tipped gas burners 13 to which gas is supplied through a piping system 14. Means are provided, but not shown, for reciprocating the channel members back and forth over the burners. Scraper blades 15 are provided for each channel and a hopper 16 collects the carbon black scraped from the channel members. A conveyor 60 removes the carbon black from the hopper.

Each burner produces a fish-tail shaped flame 17 and the result of the combined effects of the flame is to produce a smoky zone 18 in the upper portions of the building which extends in part over the flames themselves, but not sufficiently to smother the combustion. The zone of heavy smoke terminates somewhat above the flames as indicated by the line 19.

In normal operation when controlled by the present invention, each burner tip supplies approximately 82 cubic feet of natural gas per day, this being an increase of approximately 5% over the amount burned per burner under the previous system. This control is accomplished in its preferred form by means of a heat-sensitive element 20 which is stationed above one of the channel members 12. Preferably, a channel member is selected which is not the outermost member. In the present instance the third channel member from the outside is selected and the heat-sensitive element is mounted approximately 14 inches above it and extends longitudinally along the channel member. The longer the element 20 the more accurate are the results, but in ordinary practice it is not essential that the heat-sensitive element be unduly extended. In practice an element approximately 20 feet in length has proved quite satisfactory.

The heat-sensitive element 20 is a closed tube containing air or other gas and communicating through the tube 21 to the cylinder 22. This cylinder contains a liquid 23 and is provided in its upper portion with a vent opening 24 controlled by a valve 25. The liquid 23 communicates with the line 21 and with the diaphragm valve 28 which is secured to a frame 29 by means of the bolt 30. A spring 31 is positioned around the bolt 30 and tends to push the diaphragm 32 downwardly against the pressure of the liquid 23.

Variations in pressure within the diaphragm 28 are communicated to diaphragm valve 33 which adjusts the throttle valve 34 in the by-pass line 35 which takes gas from the main supply line 14. The by-pass line 35 communicates with the third diaphragm valve 36. A line 37 communicates with the other side of diaphragm 36. Adjustments of the throttle valve 34 control the pressure differential on the valve 36 which in turn controls the setting of the main control valve 26.

The pressure of the gas within the tube 20 is adjusted to produce optimum operations at a given time. Thereafter if the temperature on the element rises, pressure therein also rises. This is communicated to the gas control valve 28 and diminishes the amount of gas delivered to the burners. It has been found generally satisfactory to use only one such control in a series of buildings, but an element may be used in each building if desired.

On the other hand, if the temperature on the tube 20 falls, the pressure therein also falls and the gas control valve 26 is operated to increase the flow of gas to the burners. It has been found that under all normal operations no control of the draft need be made, the control being limited to increasing or decreasing the amount of gas

supplied. This has been found to be true in extended tests of the control.

The use of fluid pressure is very simple and more accurate than ordinary temperature regulators. This is particularly true because an extended tube 20 will balance out any irregularities in combustion conditions beneath it, and the combustion conditions in the chamber do not depend upon any one burner but upon the group effect of the whole set.

The combination of a gas filled element, in direct contact with the high temperature zone, and a liquid filled element, controlled thereby, is of particular value in a system as extensive as is found in carbon black plants. The use of an entire communicating system filled with gas would be inadvisable because of the fact that the gas, being compressible, loses its effect with distance. On the other hand, it is desirable to have a highly expandable material in the high temperature zone. The present system combines an incompressible liquid control with a highly expandable gas control.

In Figure 4 a simplified system for a plant of forty-two burner buildings, in which only two controls are employed, is diagrammatically illustrated.

The line 50 is a header which is connected by a number of pipes 51 to the burners in each of the burner houses 52. These are arranged twenty-one on each side of the header, each building being approximately 180 feet long by 10 feet wide. Gas is supplied to the header 50 through two supply lines 53 and 54, one of which is connected to the header as shown at 55 about one quarter of the distance from one end to the other, and the other header is connected at a point 56 similarly located with respect to the other end of the header. The supply of gas is then controlled by the valves 26a and 26b, each of which is in turn controlled by a temperature responsive system such as heretofore described.

The valve 26a is controlled by a temperature responsive element in one of the twenty-one buildings on its side of the header, preferably a building at least three buildings from the end of the row. The valve 26b is similarly controlled by a temperature responsive element in a similarly located building on its side of the header.

With this type of system it is of course possible for one of the valves 26a and 26b to be supplying more gas than normal, while the other is supplying less, but the system has been found very satisfactory in actual practice.

The foregoing detailed description has been given for clearness of understanding only, and no unnecessary limitations should be understood therefrom.

What I claim as new, and desire to secure by Letters Patent is:

1. In the production of carbon black, in a system in which a plurality of individual gas burners of the impingement type are operated in proximity to chilled members within a structure having substantially fixed draft inlet and outlet openings, and having no mechanical draft regulation system, the method which comprises automatically regulating the flow of gas to the burners in response to temperature-sensitive means, to produce a greater flow of gas to the burners when the temperature at points adjacent impingement surfaces in the combustion zone falls too low, and a smaller flow of gas to the burners when the temperature is too high.
2. In the production of carbon black, in a sys-

tem in which a plurality of individual gas burners of the impingement type are operated in proximity to chilled members within a structure having substantially fixed draft inlet and outlet openings, and having no mechanical draft regulation system, the method which comprises introducing a greater flow of gas to the burners when the temperature at points adjacent impingement surfaces in the combustion zone falls too low and reducing the flow of gas to burners when the 10 temperature is too high.

3. The method as set forth in claim 1 in which the regulation is carried out by pressure means directly responsive to temperature conditions at a predetermined point in the combustion system.
- 5 4. The method as set forth in claim 2, in which the flow of gas is controlled automatically in response to pressure in an elongated pipe in the combustion zone.

LEONARD M. CONNER.
